ATTORNEY.

UNITED STATES PATENT OFFICE.

CHARLES TASSO AND HUBERT B. DALY, OF NEW YORK, N. Y.

MUFFLER.

Application filed August 15, 1919. Serial No. 317,784.

To all whom it may concern:

Be it known that we, CHARLES TASSO and HUBERT B. DALY, citizens of the United States, residing at New York, in the county 5 of New York and State of New York, have invented new and useful Improvements in Mufflers, of which the following is a specification.

This invention relates to improvements in 10 mufflers and has for its principal object to provide a muffler provided with a safety valve for permitting the escape of excess pressure and avoiding the destructive effects of explosion occurring within the muffler caused by what is termed "a back fire".

Heretofore, in the construction of mufflers for motor vehicles it has been customary to provide a cylinder formed of a thin sheet metal shell arranged with a series of 20 baffles for breaking up and retarding the passage of the exhaust gases to avoid much of the noise usually accompanying the use of motor vehicles or internal combustion engines.

25 It has been frequently experienced in the use of such mufflers that a back fire in the muffler would cause the shell to be blown therefrom, thereby destroying the utility of the same and putting the user to considerable expense for the repair of the muffler.

As another object the present invention contemplates the provision of a muffler constructed of cast metal which is designed to avoid the objections to the ordinary type of 35 muffler and a back firing occurring within the same.

A more specific object of the invention is to provide a combination pressure relieve valve and cut-out which is designed to take 40 care of any excess pressure occurring within the muffler, thereby materially reducing danger of injury to the muffler.

With these and other objects in view, the invention consists in the novel construction, 45 combination and arrangement of parts which will be fully set forth in the following specification, claimed and illustrated in the accompanying drawing in which:—

Figure 1 is a side view of a muffler constructed in accordance with this invention.

Figure 2 is an end view thereof, and

Figure 3 is a longitudinal sectional view through the device.

Referring to the drawings in detail, the 55 numeral 5 designates in its entirety, the

main body of the muffler provided with the inlet and outlet nozzles 6 and 7, respectively. The main body consists of a pair of castings 8 and 9 which are of substantially circular formation and provided with mating flanges 60 which when assembled form the entire muffler. It will be understood that the castings 8 and 9 are provided with extensions, the edges of which are matched and arranged when assembled to provide the nozzles 6 and 7. Formed integrally with the nozzle 6 at a point near the muffler 5 is a depending tubular extension 10 formed at its lower end with an annular valve seat 11, while a boss 12 is formed at a point diametrically opposite the 70 extension 11 and is provided with an axial opening to receive the valve stem which will be more fully hereinafter described. Formed on the castings 8 and 9 adjacent the boss 12 are upwardly extending ears 13 between 75 which is pivotally mounted the valve actuating lever which will be more fully herein-after described. The casting 8 is formed interiorly with a plurality of baffle plates 14 and 15 arranged preferably in the manner illustrated in Figure 3. It will be understood, however that these baffle plates may be arranged at varying angles and may be modified to meet varying requirements 80 without departing from the spirit and scope 85 of the invention. These baffles while extending well into the casting 9 terminate slightly short of the inner face of the side wall thereof in order to provide a clear passage through the device which materially assists 90 in the conducting of exhaust gases therethrough and yet will not interfere with the effect of the baffles in breaking up the gases and destroying the sound of the emission 95 thereof.

As illustrated in Figure 2, the casting 9 is provided with a bracket 16 which may be attached to any portion of the chassis of a vehicle.

In order to close the opening through the extension 10, a valve 17 is arranged to seat on the valve seat 11 and this valve is provided with a stem 18 which extends through the boss 12 and is surrounded adjacent its outer end with a spring 19 bearing on a plate 100 20 which engages with a cotter pin 21 passing through said stem. It will be understood that the opposite end of the spring 19 bears on the boss 12 and it will thus be seen that the valve 11 will be yieldably 110

held against the seat 11. In order to provide a means for opening the valve in the manner of an ordinary cut-out, a bell crank lever 22 is pivoted between the ears 13 and 5 is connected, by a flexible member 23 to a suitable actuating mechanism (not shown) near the seat of the operator. The opposite arm of said bell crank lever is positioned directly over the outer end of the valve 10 stem 18 and it will be obvious that when pull is exerted on the member 23, the lever will be rocked thereby causing the valve to open. In use, the device is connected to the exhaust pipe of a motor vehicle by attaching 15 the nozzle 6 thereto and it will be obvious that the exhaust gases entering the motor will be broken up and the noise usually accompanying the emission of said gases will be reduced to a minimum. Should a back 20 fire occur within the muffler, it will be obvious that not only will the gases be exhausted through the nozzle 7 but they may also back into the nozzle 6 and due to the high pressure thereof, the tension of the 25 spring 19 will be overcome thereby opening the valve 7 and permitting the escape of the gases through the tubular extension 10. Should it be desired to open the valve in the manner of an ordinary cut-out as is frequently done when negotiating a hill or 30 hard pull in order to relieve back pressure, it will be obvious that the flexible member 23 may be pulled thereby opening the valve

and avoiding the necessity of forcing the exhaust gases through the muffler.

While in the foregoing there has been shown and described, a preferred embodiment of this invention, it is to be understood that certain minor changes in the details of construction, combination and arrangement 40 of parts may be resorted to without departing from the spirit and scope of the invention as claimed.

What is claimed as new is:—

A muffler comprising a hollow circular 45 body portion having vertical side walls, an inlet extension formed thereon at the top of said body portion, an outlet extension formed at the bottom of said body portion, baffles formed integral with said body portion and projecting from the circular walls and terminating short of said vertical side walls, the baffles of one side of said circular walls overlying the baffles of the opposite side to provide a passage way from the inlet extension to outlet extension, and a valve 50 mounted in the inlet extension and disposed at a right angle to the axis thereof and operable from a point distant from the muffler for relieving excess pressure in said body portion.

In testimony whereof we have affixed our signatures.

CHARLES TASSO.
HUBERT B. DALY.
